UNITED STATES PATENT OFFICE.

MIKE W. HERMES, OF BULGER, PENNSYLVANIA.

TROLLEY-WIRE EXTENSION-SPICE.

1,393,530.

Specification of Letters Patent.

Patented Oct. 11, 1921.

Application filed March 18, 1921. Serial No. 453,507.

To all whom it may concern:

Be it known that I, MIKE W. HERMES, a citizen of the United States, residing at Bulger, in the county of Washington and

5 State of Pennsylvania, have invented new and useful Improvements in Trolley-Wire Extension-Splices, of which the following is a specification.

This invention relates to trolley wire 10 splices, and more particularly to what I term a trolley wire extension splice.

One of the main objects of the invention is to provide a trolley wire splice which may be adjusted to accommodate expansion and 15 contraction of the wire. A further object is to provide a splice of the character stated of simple construction and operation which may be readily applied and may be manufactured at small cost. Further objects will 20 appear from the detailed description.

In the drawings:

Figure 1 is a side view of a splice constructed in accordance with my invention.

Fig. 2 is a top plan view of the splice.

25 Fig. 3 is a section taken substantially on line 3—3 of Fig. 2.

Fig. 4 is an enlarged fragmentary section through one of the securing blocks and associated parts.

30 In constructing the splice I provide an elongated sheet metal casing 1 of substantially U shape in cross-section. A securing block 2 is slidably mounted in this casing adjacent to each end thereof, these blocks 35 being formed of brass or any other suitable or preferred material. Block 2 is provided with a vertical bore communicating at its lower end with a groove in the underface of the block, the groove being adapted to 40 receive a trolley wire 3 the end portion of which is turned upwardly at right angles to provide a vertically disposed arm 4 which projects through the bore in block 2, this arm being secured by a set screw 5 threaded 45 into the block.

Each block is provided with a threaded rod 6 extending from its inner face, these rods being threaded into sleeves 7 of a turn buckle 8 provided at its central portion with 50 a squared shoulder 9 adapted to fit snugly between the arms of casing 1 so as to lock the turn buckle against rotation. As will be understood, one of the rods 6 is provided with a left-hand thread, the other rod having a right-hand thread. To permit adjustment of blocks 2 toward and away from

each other, casing 1 is provided adjacent to each end of each side wall with a longitudinally extending slot 10 through which projects a securing screw 11 which passes 60 through block 2 and, normally, coöperates with a nut 12 and block 2 for clamping the side walls of the casing. By removing casing 1 blocks 2 may be readily adjusted toward or away from each other by means of 65 the turn buckle so as to take up any slack in the trolley wire, or relieve excessive tension, as conditions may require.

If desired, though not necessarily, each block 2 is provided with a laterally projecting lug 13 which is bored to receive the end portion of a wire 14, this wire being secured by means of set screws 15 threaded into the lugs. This insures electrical connection between blocks 2 though, under ordinary conditions, the casing 1, being held tightly against the blocks by screws 11 and nuts 12, will act as a conductor to establish electrical connection between the blocks.

The device constructed in the manner illustrated and described may be readily applied to a trolley wire of standard type and provides simple and efficient means whereby contraction or expansion of the wire may be accommodated. It may be found desirable in practice to resort to changes in details of construction and arrangement of parts of the invention, and I intend to include all such variations, as fall within the scope of the appended claims, in this application in which a preferred form only of my invention is disclosed.

What I claim is:

1. In a device of the character described, a casing, blocks mounted in said casing and 95 adjustable toward and away from each other, means for simultaneously adjusting said blocks, and means for securing the blocks in adjustment and for forcing them into tight contact with the casing.

2. In a device of the character described, a casing, blocks mounted in said casing adjacent the ends thereof, means for securing the ends of adjacent sections of a trolley wire to said blocks, and means coöperating 105 with said casing for simultaneously adjusting the blocks toward and away from each other and for securing said blocks in adjustment.

3. In a device of the character described, 110 a casing, blocks mounted in said casing adjacent the ends thereof, means for securing

the blocks to the adjacent ends of sections of a trolley wire, rods projecting from the inner faces of the blocks, and a turn buckle threaded on said rods and provided with means for coöperating with the casing for normally holding the turn buckle against rotation.

4. In a device of the character described, a casing, blocks slidably mounted in said

casing and held against rotation therein, rods projecting from the inner faces of said blocks, and a turn buckle threaded upon said rods and provided with an element fitting snugly between the walls of the casing so as to normally hold said turn buckle against turning movement.

In testimony whereof I affix my signature.
MIKE W. HERMES.
